TRACTION WHEEL

Joseph L. Hecht and Ernest E. Einfeldt, Davenport, Iowa, assignors to French & Hecht, Incorporated, a corporation of Iowa

Application April 27, 1933, Serial No. 668,156

12 Claims. (Cl. 301—41)

This invention relates to traction wheels for motor vehicles, tractors and the like, and more particularly to means for varying the tractive effect of the driving wheels of such vehicles, according to the demands and conditions to be met in their operation.

The present invention contemplates the provision of weights which may be readily applied to and removed from the wheels of the machine, and which are so constructed that different numbers of the weights may be utilized at the same time, and as desired, to meet a particular demand. Further, the invention provides a compact arrangement of the weights on the wheels so as to maintain their centers of weight in as close proximity to that of the wheel as possible, and to permit a maximum of weight to be disposed within a limited space.

To these ends, the weights are constructed in the form of annular members or rings adapted to be arranged on the wheel in series radially, or nested thereon, in the space between the hub and rim of the wheel, the weights being secured in place by fastening means adapted to be associated with one weight only regardless of the number of weights which are applied to or fitted on the wheel. More specifically, the weights are adapted to fit one around the other, and are cone-shaped and formed with correspondingly beveled contiguous surfaces, so that each weight subsequently fitted on the wheel will engage and wedge or clamp in place the weight previously fitted thereon. The fastening means, in the form of hook-bolts adapted to engage the spokes of the wheel, are associated with the weight last applied, and hence, through the weights themselves, a single circle of bolts serves to secure all of the weights to the wheel.

In the accompanying drawings, the invention has been shown merely by way of example and in preferred form, and obviously many variations and modifications may be made therein which will still be comprised within its spirit. It is to be understood, therefore, that the invention is not limited to any particular form or embodiment, except insofar as such limitations are specified in the appended claims.

Referring to the drawings:

Fig. 1 is a vertical transverse section through the wheel equipped with one of the improved weights;

Fig. 2 is a vertical transverse section of a portion of the wheel equipped with two weights;

Fig. 3 is a view similar to Fig. 2, showing the wheel equipped with three weights;

Fig. 4 is a vertical transverse section through the wheel equipped with a modified form of the improved weight;

Fig. 5 is a vertical transverse section of a portion of the wheel equipped with two weights of modified form;

Fig. 6 is a view similar to Fig. 5, showing the wheel equipped with three weights;

Fig. 7 is a vertical transverse section of a portion of the wheel equipped with weights of still another modified form; and

Fig. 8 is a face view of the wheel fully equipped with weights of the preferred form.

The wheel illustrated in the accompanying drawings comprises a hub 1 and a rim 2, which are connected in the usual manner by spokes 3. The wheel may be of any desired construction and adapted to carry a pneumatic tire T (as illustrated) or to carry a cushion rubber tire, or it may be in the form of an all metal tractor wheel.

As already stated, the present invention is directed to the application of weights to the wheel in order to increase its tractive effect, and contemplates a compact arrangement of the weights to permit a maximum of weight to be disposed most effectively within a limited space.

In the preferred embodiment of the invention, which is illustrated in Figs. 1, 2, 3 and 8, a series of weights 5, 6 and 7, in the form of rings having different diameters, are adapted to be applied or fitted to the outside of the wheel and arranged thereon in nested condition, or in series radially, being secured to the wheel by hook-bolts 8, the inner hooked ends 8^b of which engage with the spokes 3 of the wheel. Referring particularly to Fig. 1, the weight 5, which is the weight first applied to the wheel, is formed so that a surface 10 thereof, which is adjacent the rim 2 of the wheel, substantially follows the contour of the rim, thus enabling the maximum amount of weighting material to be employed in the weight. However, in order to allow for discrepancies in manufacture and to insure that the weight 5 will readily fit the wheel to which it is to be applied, it is formed so that only a portion 11 of the surface 10 will contact with the rim 2, the portion 11 being adapted to engage with the under surface of the tire bead seat 2^a, the diameter of which is the same for all rims adapted to carry a pneumatic tire of a given size. The surface 5^a of the weight 5 is formed with a recess 12 to provide lugs 13 and 14, in each of which there is formed a recess or groove 15 adapted to receive one of the fastening bolts 8, the weight being

100
105
110

formed in this manner in order to facilitate the fashioning of the grooves 15, which have a depth greater than the diameter of the bolts 8. With this construction and arrangement of the parts, 5 it will be noted (see Fig. 1) that the weight 5 may be fitted to the wheel, and the bolts 8 engaged with the spokes and fitted into the grooves 15, whereupon tightening of the nuts 8^a on the bolts 8 will draw the weight toward the spokes 3 and securely clamp it in position on the wheel. It 10 will also be noted that two bolts only are required to secure the weight to the wheel, although, of course, a greater number of bolts may be employed.

15 Coming now to the application of additional weights, the surface 5^a of the weight 5 is cone-shaped, so that when the cone-shaped weight 6 is applied, it fits snugly into position with its correspondingly beveled or cone-shaped outer surface 6^a in contact with the surface 5^a of the weight 5. When the weight 6 has been thus applied to the wheel, the nuts 8^a are loosened, and the bolts 8 shifted from the grooves 15 formed in the weight 5, to grooves 16 formed in the 20 weight 6, and the nuts 8^a tightened to fasten the weight 6 to the wheel, which weight, by its wedging engagement with the weight 5, holds the latter in place, as shown in Fig. 2. When still another weight, such as the cone-shaped weight 7, 25 is to be applied, it is fitted within the weight 6, as shown in Fig. 3, a cut away portion 7^c permitting it to overlie the outer edge 1^a of the hub 1. The outer surface 7^a of the weight 7 is beveled for engagement with the inner surface 6^b of the 30 weight 6, which is correspondingly beveled. The bolts 8 are shifted from their position in engagement with the weight 6 to grooves 17 formed in the surface 7^b of the weight 7 for fastening the latter to the spokes 3, the weight 7 holding 35 the weight 6 on the wheel, while the weight 6 in turn holds the weight 5 on the wheel. Thus it will be seen that with the weights 5, 6 and 7 formed and arranged on the wheel in the manner just described, an interlocking engagement of the 40 weights is effected so that a single circle of bolts, consisting of two or more, associated with the weight last applied, serves to secure all of the weights on the wheel, and in such manner that the load is carried by the spokes and rim of the wheel 45 and not by the projecting hub.

50 Figs. 3, 4 and 5 illustrate a modification of the invention, wherein the weight of smallest diameter is the weight adapted first to be applied to the wheel. This weight 20, as shown in Fig. 4, is cone-shaped and formed with a cavity 21 adapted to receive the outer portion 1^a of the hub 1, the portion 22 of the weight 20, which forms the wall of the cavity 21, being adapted to seat upon shoulders 4 of the spokes 3. The weight 20 is 55 formed with grooves 23 adapted to receive the hook-bolts 8 which fasten the weight in place, in the manner already set forth in the description of the preferred embodiment of the invention. With this form of weight, the latter is carried solely by the spokes, upon the shoulders of 60 which it rests and with which the bolts 8 engage, there being no engagement of the weight with the hub 1.

65 In this embodiment of the invention, the outer surface 20^a of the cone-shaped weight 20 is beveled so that when the weight 25 next to be applied to the wheel and which is formed with a correspondingly beveled surface 25^a, is fitted over the weight 20, the engagement of the surface 25^a 70 with the surface 20^a of the weight 20 will hold

the latter in place by a clamping action, the bolts 8 being shifted from the grooves 23 to grooves 26 formed in the outer surface 25^b of the weight 25. In order to effect a proper seating of the nut 8^a, or washer 8^c if one is employed, the weight is cut away as at 27 to provide a seat 28.

80 A third cone-shaped weight 30, whose surface 30^a is beveled to correspond with the beveled surface 25^b of the weight 25, is adapted to fit over the latter and hold it in place, the bolts 8 being shifted to grooves 31 formed in the surface 30^a of the weight 30. The surface 30^b of this weight is shaped to conform with the contour of the rim 2, in order to effect a snug fit when the weight is fastened in position. The opposite surface of the weight is recessed as at 32 to form a seat for the nut 8^a, the seat being flush with the seat 28 of the weight 25.

85 As in the case of the preferred embodiment, the construction and arrangement of the weights in the present instance permit the use of a single circle of bolts, associated with the weight last to be applied to the wheel, for holding all the weights in position on the wheel.

90 Another modification of the invention is illustrated in Fig. 7, wherein the manner of applying the weights to the wheel includes certain features of each of the embodiments already described. The larger weight 35, which is the weight first to be applied, is adapted to seat against the rim 100 2 of the wheel in the same manner as the weight 5 shown in Fig. 1. In order to fasten the weight to the spokes 3 of the wheel, it is formed with a bolt hole 36 extending transversely therethrough, a recess 37 being provided in the outer face of the weight to form a seat for the nut 8^a of the bolt 8, and the surface 35^a of the weight 35 is beveled in the same manner as the surface 5^a of the weight 5. The second weight 40 is wedge-shaped, being formed with opposed diverging surfaces 40^a and 40^b. A bolt hole 41 is formed in the weight, extending transversely thereof from a nut seat 42 formed in the outer face of the weight. When the weight 40 is applied to the wheel, its beveled surface 40^a engages with the 110 corresponding beveled surface 35^a of the weight 35 and effects a wedging action against the latter weight when it is drawn into position by tightening up the nut 8^a of the bolt 8. When, 115 however, a third weight 45, formed with a surface 45^a beveled in the same manner as the surface 20^a of the weight 20, is applied to the wheel, the weight 40 is removed sufficiently to permit the application of the weight 45 and then replaced with its opposed surfaces 40^a and 40^b engaging the surfaces 35^a and 45^a, respectively, and fastened in position as before. This third weight 45, like the weight 20 shown in Fig. 4, is adapted to seat on the spoke shoulders 4, and is formed with a recess 46 adapted to receive the projecting outer 125 portion of the hub 1.

130 With this construction and arrangement of the weights, the wedge-shaped weight 40 serves either to hold the weight 35 in position, or to hold both the weight 35 and the weight 45, between which it is interposed and on which it exerts a wedging action to clamp the former against the rim 2 and the latter against the spoke shoulders 4.

140 As already stated, the invention has been shown merely by way of example and in preferred form, and as applied to a particular type of wheel, and obviously many modifications and alterations of the invention will suggest themselves to those skilled in the art without departure from its scope. It is to be understood, therefore, that the invention 145

tion is not limited to any specific construction or arrangement of the parts, except insofar as such limitations are specified in the appended claims.

Having thus described our invention, what we

5 claim is:

1. A traction wheel including, in combination, a plurality of traction increasing weights in the form of annular members having different diameters and arranged on the wheel in interlocking

10 nested condition.

2. A traction wheel including, in combination, a plurality of traction increasing weights in the form of annular members having different diameters, and arranged on the wheel in interlocking

15 nested condition, and fastening means associated with one member only for holding all of the members in said nested condition.

3. A traction wheel including, in combination, a plurality of traction increasing weights secured

20 to the wheel and arranged thereon in series radially, and means associated with one weight only which fastens all of the weights to the wheel.

4. A traction wheel including, in combination, a plurality of traction increasing weights secured

25 to the wheel and arranged in series radially, the weights being formed with correspondingly bevelled contiguous surfaces, so that each weight

30 successively arranged on the wheel will engage and hold in position each adjacent weight previously arranged on the wheel.

5. A traction wheel including, in combination, a plurality of cone-shaped traction increasing weights secured to the wheel and arranged in series radially, the weights being formed with cor-

35 respondingly bevelled contiguous surfaces, so that each weight successively arranged on the wheel will engage and hold in position each adjacent weight previously arranged on the wheel, and means associated with the weight last arranged on

40 the wheel for securing all of the weights to the wheel.

6. A traction wheel including, in combination, two traction increasing weights arranged on the

45 wheel, said weights being formed to be secured in position on the wheel by a third weight inter-

posed between them and attached to the wheel.

7. A traction wheel including, in combination, a

plurality of traction increasing weights arranged

on the wheel in series radially and having oppositely beveled opposed surfaces, and wedge-shaped fastening means interposed between said weights to secure the same in position on the wheel.

8. A traction wheel including, in combination, two traction increasing weights arranged on the wheel and having oppositely beveled opposed surfaces, and an intermediate wedge-shaped weight interposed between said two weights and fastened to the wheel to secure all of the weights thereto.

9. A weight according to claim 6, characterized by the fact that the weight is wedge-shaped and formed with a series of bolt holes extending transversely therethrough.

10. A traction wheel including, in combination, a plurality of traction increasing weights arranged on the wheel concentric with the axis thereof and in series radially, and means for securing one of said weights to the wheel, said weights being constructed so that the means for securing one weight to the wheel operates to secure the other weights to the wheel.

11. A traction wheel including, in combination, an annular traction increasing weight formed with a bearing surface on its periphery for engagement with the rim of the wheel and having its radially inner surface bevelled, a second weight formed with a correspondingly bevelled radially outer surface and fitted with said surface in engagement with the bevelled inner surface of the first weight, and means associated with said second weight which secures both of said weights to the wheel.

12. A traction wheel including, in combination, an annular traction increasing weight formed to overlie the hub of the wheel and formed with a bearing surface for engagement with the spoke shoulders adjacent the hub, said weight being formed with a bevelled radially outer surface, a second weight formed with a correspondingly bevelled radially inner surface and fitted with said surface in engagement with the bevelled radially outer surface of said first weight, and means associated with said second weight which secures both of said weights to the wheel.
